Frank J. Lent

UNITED STATES PATENT OFFICE.

CHARLES WEILAND, OF NEW YORK, N. Y.

BELT OR COLLAR.

Application filed September 16, 1920. Serial No. 410,617.

To all whom it may concern:

Be it known that I, CHARLES WEILAND, a citizen of the United States, residing at New York, in the county of New York and State 5 of New York, have invented certain new and useful Improvements in Belts or Collars, of which the following is a specification.

This invention relates particularly to dog 10 collars and the objects of the invention are to provide a simple and strong buckle fastening for articles of this class, which can be cheaply manufactured and which will be neat and attractive in appearance.

15 In the preferred form of my invention the buckle is attached to the collar band or other article by means of a loop which is extended through a transverse slot in the band and covered over by a layer of backing material.

20 Other features of the invention relate to the manner in which the attachment loop is secured to the band and to the manner in which the keeper loop for the end of the strap is retained in place.

25 In the drawing accompanying and forming a part of this specification, I have illustrated the invention embodied in a simple practical form, but wish it understood that modifications and changes may be made in 30 the structure without departure from the true spirit and scope of the invention as hereinafter defined and claimed.

In the drawing referred to:

35 Figure 1 is a perspective view of the invention embodied in the form of a dog collar,

Figure 2 is a fragmentary view of the end of the outer or facing strap of the device,

40 Figure 3 is a similar view of this strap as punched to receive the buckle attaching loop,

Figure 4 is a detached view of the buckle attaching loop,

45 Figure 5 is an edge view, showing this loop as secured to the strap,

Figure 6 is a face view of these parts,

Figure 7 is a longitudinal sectional view showing the backing applied over the end of the buckle attaching loop,

50 Figure 8 is an outside view of the finished end of the strap.

The collar shown is of the usual double-ply construction and consists of an outer or facing strap 10 and an inner or backing strap 11, both or either of which may be of

leather or any suitable flexible and more or less resilient material.

The outer strap is formed near the end thereof with a transversely extending slot 12, to receive the buckle attaching loop. 60

3 designates the buckle, which may be of any suitable or usual construction and 14 designates the socalled buckle attaching loop which is shown in the form of a short strap

looped over the bar of the buckle and having its ends passed through the slot 12 to the back of the facing strap and there secured by a rivet 15, or other suitable fastening

device, whose head 15' may be ornamental. For convenience in assemblage and for 70

greater security, the ends of this buckle attaching loop may be first secured together by a row of transverse stitching, such as indicated at 16.

The inner end of the buckle attaching 75

loop is then covered by a backing strip which, in the particular instance shown, is the inner ply 11 of the collar. These two layers or plies are then usually secured to-

gether by a transverse row of stitching 17 passing through the plies and through the ends of the interposed buckle loop, and by

longitudinal edge rows of stitching, such as indicated at 18; and the ends of these two plies are shown as secured together by a 80

transverse row of stitching 19.

This construction permits of the parts being secured together entirely by machine stitching, as distinguished from hand sew-

ing, which means economy in manufacture; 90 and the construction also enables quick and easy assemblage of the related parts. The end portions of the straps which project be-

neath and beyond the buckle attaching loop also form a tongue standing in back of the 95 buckle and serving as a guard to prevent the buckle from irritating the throat of the animal.

In practice, the backing strip may be flattened down over the inner end of the buckle 100 attaching loop, so as to present practically a smooth surface at the inside of the collar,

it being understood that the proportions are somewhat exaggerated in Figure 7 for the purpose of better illustrating the relations 105 of the parts.

The buckle may be provided with a keeper loop, such as I have indicated at 20 and this

loop is secured in place by simply being loosely retained within the buckle attaching 110

loop, it being free to slide over said loop to the extent of motion permitted between the buckle and the point where the buckle attaching loop passes through the slot in the outer strap. This keeper loop is slipped in place over the outer reach of the buckle attaching loop, in back of the buckle before the ends of the buckle attaching loop are stitched together, as will be clear from Figure 4, so that no special fastenings are necessary for this keeper loop and it has a certain freedom of movement which is of convenience in engaging the end of the strap therewith and also is an aid in the disengagement 15 of the strap therefrom.

The invention provides an extremely practical and desirable mounting for a buckle which is adaptable to many uses, as will be apparent to those skilled in the art.

20 The transverse row of stitching 17 which secures the rearward portion of the buckle attaching loop may extend simply through the facing strap, as shown in Figure 5, or through both the facing strap and the backing strip, with the buckle attaching loop interposed therebetween, as indicated in Figure 7. Or if desired, the buckle attaching loop may be first secured to the facing strap by a row of stitching 17, as shown in Figure 5, and then after the backing strip is applied, as in Figure 7, another row of stitching may be extended through all these parts, either alongside or over the first row of stitching 17. Other modifications may suggest themselves to the skilled artisan, all coming within the scope of the appended claims.

What I claim is:

1. In a device of the character described, a facing strap having a transverse slot therethrough, a buckle attaching loop having its end portions extending through said slot to the back of the strap and secured thereto, and a backing secured to said strap and covering the end portions of the buckle attaching loop.

2. In a device of the character described, a facing strap consisting of a single ply of material having a transverse slot therethrough, a buckle attaching loop having its end portions passed through said slot to the opposite face of the strap and riveted thereto, a single ply backing secured to said strap and covering the end portions of the buckle attaching loop and a transverse row of stitching extending through the facing strap, the backing and the buckle attaching loop at a point adjacent one edge of the transverse slot in the facing strap.

3. In a device of the character described, 60 a single ply facing strap having a transverse slot therethrough, a buckle attaching loop having its end portions passed through said

slot to the opposite face of the strap and riveted thereto, a single ply backing secured to said strap and covering the end portions of the buckle attaching loop and a transverse row of stitching extending through the facing strap, the backing and the interposed portion of the buckle attaching loop, at a point adjacent one edge of the transverse slot in the facing strap.

4. In a device of the character described, a two-ply band having a transverse slot in the outer ply thereof, a looped buckle attaching strap having its ends passed through said slot and directed inward of the end of the band and in between the two plies and means for securing said interposed end portions of the buckle attaching strap between the said two plies.

5. In a device of the character described, a two-ply band having a transverse slot in the outer ply thereof, a looped buckle attaching strap having its ends passed through said slot and directed inward of the end of the band and in between the two plies and means for securing said interposed end portions of the buckle attaching strap between the said two plies and comprising a transverse row of stitching adjacent the edge of the slot.

6. In a device of the character described, a facing strap having a transverse slot, therethrough, a buckle, an attaching strap looped through said buckle and having its end portions extended through the slot and directed inward of the end of the strap and against the back of said facing strap, means for securing said rearwardly extended portion of the buckle attaching loop at the back of the facing strap and a keeper loop loosely and slidably retained in the buckle attaching loop between its point of passage through the facing strap and the rear of the buckle.

7. In a device of the character described, a facing strap having a transverse slot therethrough, a buckle, a strap looped through the buckle and having its end portions extended through the slot and against the back of the facing strap, a backing strip secured to the facing strap and covering the rearward end portions of the buckle attaching loop, a keeper loop loosely and freely slidably in the buckle attaching loop between its point of passage through the facing strap and the rear of the buckle and a transverse row of stitching extending through the facing strap and the rearward portion of the buckle attaching loop to thereby secure said loop and to limit the sliding movement of the keeper loop thereon.

In testimony whereof I affix my signature.

CHARLES WEILAND.
